UNITED STATES PATENT OFFICE

JAMES E. BLACK, OF EAST ORANGE, NEW JERSEY, ASSIGNOR TO BLACK SYSTEMS, INC.,
OF CHICAGO, ILLINOIS, A CORPORATION OF ILLINOIS

BUILDING COVERING

Application filed October 12, 1931. Serial No. 568,284.

My invention relates to building coverings. That is, to the protective and decorative weatherproof coverings which are applied to the roofs and outer side walls of buildings, usually in the form of individual or multiple units—generally called shingles—or in strips. In some forms the strip covering units are commonly termed “roll roofing”.
10 The invention has particular reference to the anchorage upon building roofs or side walls of flexible units, such as those formed from the various well known varieties of prepared sheet roofing material. Such material, as now generally used, comprises asphaltum impregnated paper stock or “felt” which is sometimes provided on one surface with a protective and decorative coating of crushed stone or other resistant material and 15 sometimes used plain.

One of the difficulties encountered in the use of such units of flexible material is that of adequately anchoring the butt or exposed end. Metal anchorages, such as ordinary 20 roofing nails, are the most satisfactory from the standpoint of security and expense but their use without exposing the metal to the elements—sun and moisture—is a troublesome problem.

Various methods and arrangements for concealing and protecting metallic butt-anchorages have been developed, but those which are satisfactory from a maintenance 25 standpoint are either too expensive to produce or install or too difficult to handle with unskilled labor to permit them being adapted on the cheaper installations.

One of the objects of my invention is to provide a building covering which is inexpensive to produce and apply and yet the metallic butt-anchorages are concealed and protected against the action of the elements.

Another object is to provide a covering composed of simple, attractive and, in general, conventional forms and styles of units which, however, may be securely and cheaply anchored adjacent the butt or exposed edge with ordinary roofing nails without the nails showing.

50 Another object is to provide a cheap and

effective method for concealing metallic butt-anchorages.

Other objects and advantages will herein-after appear.

Several typical embodiments of my invention—chosen with the idea of exemplifying the wide variety of its application—are shown in the accompanying drawings, wherein

Fig. 1 is a front view of a unit of conventional rectangular shape as I would prefer to produce and supply it for application in accordance with my invention;

Fig. 2 is a similar view of the same unit with the lowercorner removed to provide the exposed or butt edges for the conventional hexagonal design covering and the key for covering the butt-anchoring nail;

Fig. 3 is a front view of a section of covering composed of units such as illustrated in Figs. 1 and 2 anchored in accordance with my invention;

Fig. 4 is a phantom perspective view, partly in section, of a unit with its butt anchored and the tip slightly elevated to illustrate how the key is applied from the rear and retained and how it functions;

Fig. 5 is a front view of a section of covering composed of strip units anchored according to my invention and wherein the anchorage covering keys are applied from the front;

Fig. 6 is an enlarged perspective view, partly in section, illustrating the method of applying a covering such as shown in Fig. 5;

Fig. 7 is a perspective, partly in section, of a portion of a unit arranged according to my invention and using an anchorage covering key of modified form for front application;

Fig. 8 is an enlarged perspective of the key used in Fig. 7;

Fig. 9 is a separated front view of a portion of a unit in the form of a strip, such as is particularly appropriate for side walls, and of the anchorage covering key also in strip form;

Fig. 10 is a front view, in reduced scale, of a section of covering composed of strips such as shown in Fig. 9;

Fig. 11 is a perspective view illustrating

the application of strip units and keys shown in Fig. 9 to produce the effect or design shown in Fig. 10;

5 Fig. 12 is a perspective view illustrating a different method of applying strip covering units;

10 Fig. 13 is a perspective view, in reduced scale, of a strip unit adapted for application as shown in Fig. 12;

15 Fig. 14 is a front view, in reduced scale, of the design produced by the application of strip units such as shown in Fig. 13 in accordance with the method illustrated in Fig. 12;

20 Fig. 15 is a front view of a modified form of unit, particularly adapted for side wall covering, in the application of which a part of an adjacent unit forms the key for concealing the butt anchorage nail;

25 Fig. 16 is a front view of an assembly of two such units to illustrate how a part of one conceals the butt-anchorage of the other;

30 Fig. 17 is an enlarged perspective view, partly in section, illustrating further how a part of one unit acts as a key to conceal the butt-anchorage of an adjacent unit;

35 Fig. 18 is a front view, in reduced scale, of a section of covering formed from units such as illustrated in Figs. 15 and 16;

40 Fig. 19 is a front view of another modification, particularly adapted for the anchorage of strip units when they are laid vertically; and

45 Fig. 20 is a perspective and partial section, on an enlarged scale, illustrating the application of units to produce the effect shown in Fig. 19.

50 The term "unit" as heretofore and herein-after employed embraces all of the usual basic forms of building coverings, such as individual, multiple and strip shingles, so called "roll roofing" and siding.

55 Referring first to Figs. 1 to 4 the unit comprises a rectangular sheet of flexible prepared roofing material, which, in the embodiment illustrated, is adapted to have its lower corner removed so that it may be laid to produce the conventional hexagonal design on the building. The removed corner constitutes the key for concealing the butt anchoring nail, as will be hereinafter described. Thus, as produced and supplied to the trade the lower corner 6 is in place, as shown in Fig. 1, but by a series of cuts or indentations 7 it is rendered readily separable from the body. When the corner is removed the body edge 8 forms the butt edge of the applied unit as shown in Figs. 3 and 4. An opening 9 is cut through the unit near the butt edge 8 in such a way as to provide a tongue 10 the upper end of which is free and the lower end of which is integral with the unit body. Thus, as illustrated, this opening may be composed of two angularly related slits 11 and 12 diverging downwardly and outwardly

from a common meeting point toward the butt of the unit. This arrangement provides an upwardly pointed triangular shaped tongue. Additional small slits 13 and 14, joining the slits 11 and 12 respectively substantially at right angles thereto, provide small shoulders for meeting the diverging edges of the key when the same is inserted and serve to facilitate the application of the key and to prevent the tearing of the unit by the key. In this manner the opening through the shingle provides a tongue, adjacent the butt edge, through which a nail 15 may be driven to anchor the butt of the unit firmly to the building framework. This nail when applied is exposed but, since it firmly holds down the tongue, the raising of the rear or tip end of the body of the unit separates the tongue from the rest of the unit body along the lines of the slits 11 and 12 and thereby forms a hole through the unit. This hole permits the triangular key 6, after being slipped behind or underneath the unit, to be inserted outwardly through the opening therein and above the tongue to cover the nail. By making the distance separating the shoulder forming slits 13 and 14 sufficiently less than the maximum width of the triangular key, the key may be forced through the opening in the body of the unit sufficiently far adequately to cover the nail and yet not so far but what the upper end thereof will lie above and behind the apex of the opening.

55 When the tip of the unit is subsequently laid flat and anchored down the key can not be displaced by any of the usual forces which act on the covering, such as wind, contraction and expansion and the like.

60 In laying a covering composed of units such as just described the usual starting strip 16, ordinarily composed of material similar to the units, may first be nailed in position at the eave of the roof or base of the wall. Then the first or lowest horizontal course of units is applied at the properly spaced intervals for the desired design. Each unit is located and then a nail driven through its tongue 10 into the framework. When a unit has been thus anchored at the butt the tip is elevated and, since the tongue is held down by the nail, a triangular hole, defined by slits 11 and 12, is temporarily opened in the unit. Next the triangular key 6, which previously has been separated from the unit by tearing the same therefrom along the perforated line 7, is slipped behind the unit and forced from the rear out through the hole therein and above the tongue until its diverging edges firmly engage the shoulders formed by slits 13 and 14. In this position the key, which lies on top of the tongue, covers the butt-anchoring nail. The unit may now be laid flat and its tip end anchored by nails driven therethrough within the area which will be cov-

70

ered by the overlapping units of the next course. Thus each unit is securely anchored not only at its concealed tip end but also at its exposed butt end and yet the metallic 5 butt-anchorage is concealed and protected by an overlying layer of the composition roofing material like that of the unit itself.

The laying and anchoring of succeeding units in the same and subsequent courses proceeds in the same way until the entire area 10 is covered.

Of course, if the removal of a corner at the exposed or butt end of the unit is not desired the key may be provided by locating the 15 severing perforations so as to effect the removal of the corner opposite the tongue forming opening. This tip region of the unit may be so far overlapped by the succeeding course units that the removal of the upper concealed 20 corner will do no harm. Likewise, if desired, one or more tongue forming openings may be located adjacent one of the longer edges of the unit, in which event that edge will form the butt edge, while the keys may be provided 25 by forming angularly related sets of separating perforations along the opposite tip or concealed edge. It is not necessary, however, that the keys be formed initially as a part of the units as they may be produced separately.

30 The provision of units which, as made, handled, packed, shipped and stored, are complete flat rectangles or other symmetrical shapes simplifies the marketing problem because they may be packaged easily, quickly 35 and inexpensively. There are no irregularities in thickness, or projecting shoulders or other peculiarities which, unless special precautions are taken, tend to injure the adjacent units in the package. The making of the key 40 integrally with the body and attached thereto until used—although readily separated when occasion requires—also simplifies the marketing problem. It is not necessary to take precautions to insure that the customer receives 45 the requisite keys—they are always there with the units.

Figs. 5 and 6 illustrate an arrangement whereby the butt-anchorage covering key 50 may be inserted from the front rather than from the rear of the unit. Such a capability may be of special advantage in cases where, for one reason or another, it is necessary or desirable to employ strip units so wide that it is inconvenient to reach down behind them 55 properly to place the keys. With this arrangement the units 20, which are illustrated as long strips of the flexible weatherproof material, are provided with openings near the lower edge to form from the strip as 60 many anchoring tongues as desired, spaced at such intervals as to insure adequate anchoring of that butt or exposed edge. These openings are formed by cutting angularly related and joined slits 21 and 22 wherever 65 an opening is desired. These slits define up-

wardly pointed triangular shaped tongues 23 (most clearly shown in Fig. 6) for receiving the anchoring nails 24, which are driven therethrough into the building framework. Thus the butt edges of the units are securely 70 anchored down to the building. Following the application of the anchoring nail a small key 25 is inserted from the front of the unit into the opening formed by slits 21 and 22 and, lying over the tongue covers the nail. 75 The keys are preferably formed from the same material as the units and of such size and shape that they may be readily inserted from the front, will adequately cover the 80 nails therebeneath and will retain themselves in position after insertion.

A suitable form of key is shown in full perspective at the right in Fig. 6. This key is of generally keystone shape, preferably somewhat pointed at the top to facilitate its 85 insertion through the opening therefor in the unit body. The lower end is shown pointed for appearance sake only. In its middle region the key is formed with two laterally related notches 26 which give it, between 90 those notches, a width slightly less than the distance between the lower ends of slits 21 and 22.

Above and below the notches the width of the key is slightly greater than the distance between the lower ends of slits 21 and 22. Thus, by slightly bending the key longitudinally, it may be temporarily narrowed for insertion through the unit from the front. It is pushed through the opening until its 95 notches 26 register with the base of the tongue 23 whereupon, by slight pressure against the front side, it may be flattened out to its original width. When flattened the shoulders above and below the notches 100 26 will engage the edges of the tongue forming opening through the unit and the key is secured against accidental displacement.

Assuming that the laying of a covering 105 with this style of unit and key is to proceed upwardly from left to right the workman first positions the lower left hand unit—or a convenient length thereof—and applies nails through one or more of the tongues 23 into the building framework. The body of the 110 unit and its anchored tongues then lie flat in the same plane. Then the workman, by pushing downwardly upon the unsecured upper edge of the unit causes the same to 115 bend or flex outwardly away from the wall, as shown at the right in Fig. 6. However, since the anchored tongues can not follow the curvature of the body of the unit the upper free end of each is separated from the body and a relatively unobstructed hole 120 through the unit is temporarily opened for the application of the key. A key, slightly bent as previously described, is then pushed upwardly through this opening until its 125 notches 26 register with the base of the 130

tongue. The key is then in position to permanently cover the nail; it is flattened out and the unit is permitted to resume or is pushed back into its original flat condition 5 and anchored along its upper or top edge in a region which will be covered by the butt of a unit of the succeeding course. When the unit resumes its flat condition the hole there-through is effectively closed by the key. This 10 procedure is repeated throughout the laying of the first and succeeding courses until the entire area is covered.

Figs. 7 and 8 show a slightly modified arrangement for key application from the 15 front, wherein it is unnecessary to flex the units to facilitate the positioning of the keys. In accordance with this modification the upwardly pointed tongues 27 are formed in the units as previously described. Keys 28 of 20 substantially U shape are used. The yoke 29 of the key forms the nail covering while the legs 30 afford ready handles for applying it. The distance between the legs is somewhat greater than the width of the base 25 of the tongue of a unit while the yoke of the key is made deeper than the length of the tongue so that, when in final position, it will extend above the apex of the opening through the unit, as indicated at the left in 30 Fig. 7.

In using this construction a key is placed beneath the unit with its yoke 29 above the location of the point of an overlying tongue and with its legs at opposite sides of the 35 tongue as shown at the right in Fig. 7. Then the anchoring nail is driven through the tongue into the building framework. The head of the nail will draw the free end of the tongue inwardly between the legs of the key 40 and against the building but, because of the interposed key, the body of the unit can not follow the tongue. The result is that the upper free end of the tongue will be drawn inwardly out of the plane of the adjacent 45 parts of the unit and the key then may be drawn down over the tongue to cover the nail, as shown at the left in Fig. 7. The key is then forced into final position by pulling downwardly upon its legs, which are 50 made long enough to project below the lower or butt edge of the unit so that they may be easily grasped. After the key has been tightly wedged between the tongue and body of the unit a further pull will separate the 55 legs from the yoke and the key will not project below the lower or butt edge of the unit. Such separation may be facilitated by providing lines of relative weakness 31 in the region where the legs join the yoke. Inden-tations or partial cuts will insure the desired 60 result.

Figs. 9 to 11 show how keys in the form of strips may be used to cover the anchoring nails and also afford an appearance of mor-tar joints in simulation of brick work. In 65

this type of construction the units 35 are in the form of strips of any appropriate length. The anchorage receiving tongues are formed therein by providing openings in the form of pairs of vertical parallel slits 36 interconnected by horizontal slits 37. The lower ends of slits 36 terminate above the lower or butt edge of the unit and therefore provide a plu-rality of tongues 38, the upper ends of which are free and the lower ends of which are 70 integral with the body of the unit. The number of and spacing between tongues may be varied to suit the particular conditions to be met. In order to afford the appearance of mortar joints and brickwork the lower 75 edges of the units are banded with a stripe 39 colored, in any desired manner, to give the requisite contrast or color in simulation of mortar. The lower ends of the vertical slits terminate at or slightly below the upper 80 edge of the band of contrasting color. The keys comprise strips of material 40 which may be of any desired length and, when mor-tar jointed brickwork is to be simulated, should be surfaced to correspond to the con-trasting bands 39 of the units. 85

In applying this type of covering each unit is placed in proper position and nails 41 driven through its tongues 38 into the frame-work. Then the upper portion of the unit is 90 lifted slightly away from the building and, because the tongues are anchored, separated slightly from its tongues. Next the key strip is placed behind the body of the unit and over or in front of the tongues and the unit 95 is laid back against the framework and nailed thereto along the upper edge in a re-gion which will be covered by the unit of the next succeeding course. The key strip therefore serves not only to cover and con-100 ceal the butt anchorages of the units but also to provide the vertical bands of contrasting color which simulate the vertical mortar joints of brickwork. By having the bases of the tongues join the body of the unit at or 105 slightly below the upper edge of the band of contrasting color along its butt, it is as-sured that there will be the proper regis-tration to simulate brickwork when the key strip has been wedged down against the bases 110 of the tongues. 115

Figs. 12 and 14 show an arrangement us-ing a strip key of contrasting appearance to provide alternately different areas of about the same size. Here the unit 45 of strip form 120 has its vertical tongue-forming slits 46, which are interconnected by horizontal slits 47, spaced further apart so that alternate areas of the unit and a contrasting key strip 48 are exposed. The paired vertical slits 46 and associated interconnecting horizontal slits 47 form relatively wide tongues 49 through which the anchoring nails 50 are driven and over which lay relatively wide 125 sections of the key strip to cover and conceal 130

the nails and provide corresponding areas of a different shade, color or other contrasting effect.

- Figs. 15 to 17 show how a part of one unit 6 may act as the anchor concealing key for an adjacent unit. According to this arrangement each unit 55 has a tongue forming opening adjacent one end. This opening is produced by angularly related slits 56 and 57 10 which define an upwardly pointed triangular shaped tongue 58 for receiving the butt-anchor. The opposite corner of the unit is cut away to form a notch 59 which permits that end of the unit to be inserted behind the 15 opposite tongued end of the adjacent unit in the same course but with the tongue of the adjacent unit at the left covered thereby. In applying this construction of covering to a building the units illustrated are laid successively in each course from left to right. Thus, as best shown in Figs. 16 and 17 the unit 55a is first positioned and a nail 60 driven through its tongue to anchor the same against the framework. The upper edge of 20 the anchored unit is then pulled outwardly as indicated in Fig. 16, to separate the upper end of the tongue therefrom and the notched end of the next unit 55b is inserted therebehind. Pushing the unit 55b downwardly causes the part thereof above notch 59 to overlie the tongue of unit 55a, and serve as the key covering the nail, and to wedge between that tongue and the body thereof so that its left edge is anchored in place by the 25 overlying unit in the same course. The laying of subsequent units in the same and following courses proceeds in the same way, the tip edges thereof being nailed to the framework in regions which will be covered by the 30 units of the next higher course. To prevent the tearing of the units at the ends of the tongue forming slits, those slits may be caused to terminate in slightly enlarged holes 61 which will serve the desired purpose.
- 45 Figs. 19 and 20 show a modification particularly adapted for concealing the anchorages when units are applied in vertically disposed strips. Each unit 65 has tongue forming openings arranged along one edge. These 50 openings are in the form of slits 66 which extend from one edge (the left edge in the units shown) inwardly a sufficient distance to accommodate the keys. Each key 67 is a separate rectangularly shaped piece of material like the material composing the units. These slits form a series of tongues 68 along the edge of the unit and through which the anchoring nails 69 are driven into the framework. In applying this type of unit 55 the placement of the anchorages proceeds from the bottom upwardly. Thus a nail is driven through the lowermost tongue to anchor it to the building. Then a key 67 is applied edge-wise about midway of its length into the 60 lowermost slit 66, the upper part of the key

lying beneath the tongue immediately above the one just anchored and the lower part thereof overlying the tongue just anchored and covering the nail. Next a nail is driven through the second tongue from the bottom and through the upper part of the key therebehind into the building framework. This second nail anchors the second tongue and also the first key. This procedure is repeated until the entire strip is secured. By overlapping the unslotted edge of a unit by the slotted edge of the adjacent unit one vertical row of anchoring nails will serve to anchor the adjoining edges of two units. 70 75

Having thus explained the nature and several typical embodiments of my invention, what I claim and desire to secure by United States Letters Patent is as follows:

1. A building covering comprising a plurality of units, each consisting of a sheet of flexible weatherproof material provided with an opening which forms a tongue within the boundaries of the units near the butt edge thereof, a metal anchor applied through each tongue from the exposed face thereof and into the building framework, and a key of material like the unit overlying each tongue to cover the anchorage. 80 85 90

2. A building covering comprising a plurality of units, each consisting of a sheet of flexible weatherproof material provided with an opening which forms a tongue free of the body of the unit at one end but integral with the body of the unit at the other end, a metal anchorage applied through each tongue from the exposed side of the unit and into the building framework, and a key of material like the unit overlying each tongue to cover the anchorage. 95 100

3. A building covering comprising a plurality of units, each consisting of a sheet of flexible weatherproof material having slits therethrough to form a tongue near the butt edge thereof within the boundaries of the unit, a metal anchorage applied through each tongue from the exposed side thereof and into the building framework to attach individually the butt of each unit to the framework, and a key of material like the unit overlying each tongue to cover the anchorage thereof. 105 110 115

4. A building covering comprising a plurality of units, each consisting of a sheet of flexible weatherproof material having an opening therethrough which forms a tongue within the boundaries of the unit near the butt edge thereof, each tongue being free of the unit at one end and integral with the unit at the other end, a metal anchorage applied through each tongue into the building framework, and a key of material like the unit lying behind the body of the unit and over the tongue thereof to cover the anchorage. 120 125

5. A building covering comprising a plurality of units, each consisting of a sheet of flexible weatherproof material having com- 130

- plementary slits to form a tongue from the material of the unit, a metal anchorage applied through the tongue from the front of the unit and into the building framework, 5 and a key of material like the unit insertable so that part of the key underlies the unit adjacent the tongue and part overlies the tongue to cover the anchorage.
6. A building covering comprising a plurality of units, each consisting of a sheet of flexible weatherproof material having an opening therethrough which forms a tongue within the boundaries of the unit near the butt edge thereof, a metal anchorage applied 10 through each tongue from the front surface thereof and into the building framework, and a key of material like the unit insertable into the tongue forming opening of each unit 15 to cover the anchorage and held in place by the edges of said opening.
7. A building covering comprising a plurality of units, each consisting of a sheet of flexible weatherproof material having diverging 20 slits therein to form a triangular shaped tongue near the butt edge thereof, a metal anchorage applied through each tongue to secure the same to the building, and a key of material like the unit insertable through the 25 hole in the unit defined by the tongue to overlie the tongue and cover the metal anchorage.
8. A building covering unit comprising a sheet of flexible weatherproof material having complementary slits therein to form a tongue which may be anchored to the framework 30 to hold the unit thereto, and having a readily removable portion which forms a key to overlie the tongue and cover the anchorage.
9. A building covering unit comprising a sheet of flexible weatherproof material having complementary slits therethrough to form an anchorage receiving tongue within the 35 boundaries of the unit, and having a readily removable portion which may be detached and used to complete the finished appearance 40 of the unit when laid.
10. A building covering unit composed of a sheet of flexible weatherproof material having complementary slits therethrough to form a triangular anchorage receiving tongue 45 which may be freed from the body of the unit at one end but at the other end is permanently integral with the body of the unit near an edge thereof, and having one corner readily removable so that it may be detached 50 and used to cooperate with the slits to cover the tongue and its anchorage.
11. The combination with a building covering unit comprising a sheet of flexible weatherproof material having within its 55 boundaries an anchorage receiving tongue which may be partly separated from the unit to form an opening therethrough, and a metal anchorage applied through the tongue to assist in securing the unit to a building 60 framework, of a key composed of material

like the unit but of contrasting shade or color which is insertable behind the body of the unit to overlie the tongue to cover the anchorage and show its contrasting shade or color through the opening in the unit.

12. A building covering comprising a plurality of units, each consisting of a sheet of flexible weatherproof material having an exposed butt edge and a group of slits through the sheet near but not extending to the butt edge, said slits forming a tongue which at one end is integral with the sheet near the butt thereof and at the opposite end separable from the sheet, a metal anchorage applied through each tongue to secure the same and the butt of the corresponding unit to the underlying building framework, and a key composed of material like the unit insertable through the hole in the unit left by the separation of the tongue to overlie the tongue and cover the anchorage.

13. A building covering comprising a plurality of units, each consisting of flexible weatherproof material having an exposed butt edge and a group of slits therethrough diverging toward but terminating short of the butt edge, said slits forming a pointed tongue which at its larger end is integral with the sheet near the butt thereof and at its pointed end is separable from the sheet, a metal anchorage applied through each tongue into the underlying building framework to secure thereto the tongue and the butt of the corresponding unit and a key composed of material like the unit insertable through and engaged by the edges of the hole through the unit left by the separation of the point of the tongue to overlie the tongue and cover the anchorage thereof.

14. A building covering comprising a plurality of units, each consisting of a sheet of flexible weatherproof material provided with an opening therethrough, a metal anchor applied through each unit near the opening therethrough and into the building framework, and a key of material like the unit projecting through and held in place by the edges of the opening through the unit and overlying the anchorage to conceal and protect the same against weather.

In witness whereof, I hereunto subscribe my name this 6 day of October, 1931.

JAMES E. BLACK.
